UNITED STATES PATENT OFFICE.

OTTO ARAM, OF PHILADELPHIA, PENNSYLVANIA, ASSIGNOR TO WESTINGHOUSE ELECTRIC AND MANUFACTURING COMPANY, A CORPORATION OF PENNSYLVANIA.

COAL AGITATOR.

Application filed May 10, 1923. Serial No. 638,117.

This invention relates to fuel-feeding mechanism for mechanical stokers, particularly to agitators for fuel hoppers having a plurality of compartments or pockets in the lower portion thereof for the delivery of fuel to the furnace grate, and it has for an object to provide an apparatus of the character designated which shall ensure a uniform delivery of fuel through the hopper and especially to provide a construction which shall prevent any arching of the fuel in the hopper over the compartments by displacing at frequent intervals the fuel immediately above the upper edge of the compartment walls by means of a plowing action of an oscillatory bar.

A further object of my invention is to provide a coal agitator of the character designated which shall be more rugged, less expensive to manufacture, and which may be operated with a lesser expenditure of energy than similar apparatus now in common use.

These and other objects, which are more manifest in the further description of my invention, may be attained by the employment of apparatus illustrated in the accompanying drawings in which: Fig. 1 is a fragmentary view, partially in plan and partially in transverse section, of a hopper employed in connection with an underfeed stoker and equipped with my improved coal agitator; Fig. 2 is a view in longitudinal section of the apparatus illustrated in Fig. 1; Fig. 3 is a view of the apparatus in end elevation, the end of the hopper being removed, and Figs. 4 and 5 are views showing details of structure of the clamp.

It has been heretofore proposed in connection with coal hoppers having a plurality of pockets in the lower portion thereof to break down the arch formations over the pockets by the employment of rods which are forced back and forth through the arch in a straight side-on horizontal movement either in a direction longitudinally or transverse of the hopper.

The agitator of the present application distinguishes from these earlier devices in that deflector bars are oscillated within the hopper through zones of retarded fuel movement, the bars passing through the fuel obliquely with a glancing or deflecting stroke which acts progressively upon the fuel in zones of retarded fuel movement to deflect

the fuel away from surfaces which normally offer supports for arch formation. The arcuate paths of travel combined with the ploughing action of the bars prevent the lodgment or packing of fuel upon the interior surfaces of the hopper and ensuring a complete sealing of the fuel delivery pockets at each outward stroke of the ram.

Referring to the drawings, I show at 10 a hopper having delivery pockets 11 in the lower portion thereof formed by inclined partition walls 12 and ram housings 14. Rams 15 are provided in the housing 14 and reciprocated from a shaft 16 through cranks 17 and connecting rods 18. The shaft 16 may be supported in any suitable manner as by brackets 19 secured to the furnace front. It is to be understood that the specific constructional characteristics of the feeding mechanism above described form per se no part of the present invention and I herein set forth as illustrative of one of several conventional arrangements to which my present invention is applicable.

The agitator mechanism proper consists of a shaft 22 extending longitudinally and preferably supported by bearings 23 in the end walls of the hopper. As shown, the shaft is square in sections. Ferrules 24 fixed to the shaft at points of support serve to facilitate the rotary movement thereof. Bars or rods 26 are secured to and supported from the shaft 22 so as to rotate therewith, the bars preferably being of a U-shape and the bottom of the U-bar being substantially straight. It is desirable that the bars 26 should be so secured to the shaft 22 that the planes of the bars intersect the shaft at oblique angles. Preferably, half of the bars make with the shaft an angle opposite in direction from that of the other half, in order to equalize thrusts as will hereinafter appear. Any suitable means of securing the bars to the shaft may be employed. As shown, two cooperating clamp members 28 and 29 having centrally disposed obliquely extending notches 30, designed to embrace the shaft 22, receive the bar through apertures 31 adjacent the ends of the clamps. In assembling, the clamps 28 and 29 are placed in proper position on the shaft and the bar 26 with nuts 32 in place are inserted in the apertures 31. Nuts 33 are then drawn to hold the clamps securely to the shaft and the bars in operative relation to the clamps.

The bars 26 should be mounted directly over the partitions dividing the lower portion of the hopper into delivery pockets. A bar may be placed over each partition if desired. It is generally sufficient, however, to place a bar over alternate partitions, since an arch is eliminated by preventing the lodgment of the fuel at one side of the entrance to the pocket.

10 The shaft 22 may be oscillated by means of a conventional driving mechanism. In the drawing, a disc 35 is mounted upon the main stoker shaft and carries a connecting pin 36 near its periphery, to which pin one 15 end of a connecting rod 37 is secured. The other end of the connecting rod is secured to a crank arm 39 by means of a pin 40 carried at the outer end of the crank arm. The crank arm is bifurcated at its inner end 20 which is formed to fit over the agitator shaft 22 and to be secured thereto, as by means of a bolt 41.

The operation of my improved coal agitator is apparent from the above description. 25 In brief, the rotation of the stoker shaft 16 causes through disc 35, connecting rod 37 and crank arm 39 a continuous oscillation of the agitator shaft 22. The bars 26 which are secured to the shaft consequently swing 30 in an arcuate path and act directly upon the fuel at different levels in the hopper. The bars approach the front and rear walls of the hopper at extreme positions of oscillation and at points somewhat above the 35 upper edges of the partitions 12. As the bars approach the walls with an upwardly directed swing, they push aside the lumps of coal between the bars and walls, and thus serve to loosen the fuel which has a tendency 40 to back against the converging walls of the hopper at a point in its downward travel in advance of the pocket partitions. In their arcuate movements, the bars pass over the entire top surface of the partition walls 12 45 with only a slight clearance at the center position. The bar 26 is disposed at all times in a plane oblique to its path of travel and hence acts upon the fuel over the partition walls with a ploughing or wedging action. 50 The distance to which the fuel is laterally displaced is consequently not great, and the mechanical advantage gained by the application of forces from the bar to the fuel in this manner reduces to a minimum the energy 55 necessary to operate the agitator.

While I have shown my embodiment in but one form, it will be obvious to those skilled in the art that it is not so limited, but is susceptible of various other changes 60 and modifications, without departing from the spirit thereof, and I desire, therefore, that only such limitations shall be placed thereupon as are imposed by the prior art or as are specifically set forth in the appended claims.

What I claim is:

1. In a feeding mechanism, a relatively long and narrow hopper, a transverse partition dividing the lower portion of the hopper into fuel-discharging compartments, a 70 square shaft extending longitudinally of the hopper, a two-piece clamp provided with notches extending obliquely thereof engaging the shaft and forming therewith an oblique angle, and a U-bar secured at its 75 ends to the ends of the clamp and arranged at an oblique angle to and cutting a vertical plane passing through the longitudinal center line of the partition, and means for oscillating the squared shaft.

2. In a feeding mechanism, a relatively long and narrow hopper, a transverse partition dividing the lower portion of the hopper into fuel-discharging compartments, a 80 square shaft extending longitudinally of the hopper, a two piece clamp engaging at its center the shaft and forming therewith an oblique angle, and, a U-bar threaded at its end and secured to the ends of the clamp by nuts, the said nuts also serving to secure the 90 clamp to the shaft, the said U-bar being arranged at an oblique angle to and cutting a vertical plane passing through the longitudinal center line of the partition, and means for oscillating the squared shaft. 95

3. In a stoker feeding mechanism, a relatively long and narrow hopper, transverse partitions dividing the lower part of said hopper into a plurality of fuel discharging compartments, bars arranged to oscillate 100 above the partitions, said bars being arranged at oblique angles to said partitions, the angles at which a portion of the bars are arranged, being opposite to that of the remainder, and means for oscillating said 105 bars.

4. In a stoker feeding mechanism, a relatively long and narrow hopper, transverse partitions dividing the lower part of said 110 hopper into a plurality of fuel discharging compartments, bars arranged to oscillate above the partitions, said bars being arranged at oblique angles to said partitions, the angles at which half of the bars are arranged being opposite to that of the other 115 half, and means for oscillating said bars.

5. In a stoker feeding mechanism, a relatively long and narrow hopper, transverse partitions dividing the lower part of said 120 hopper into a plurality of fuel discharging compartments, bars arranged to oscillate above the partitions, said bars being arranged at oblique angles to said partitions, the angle at which alternate bars are arranged being opposite, and means for oscillating said bars. 125

6. In a hopper having a plurality of valleys in its bottom leading to discharge openings, the combination therewith of bars arranged to oscillate to and fro above the 130

crests between the valleys, said bars being so disposed that the horizontal projection thereof crosses at an oblique angle the longitudinal edge of the crest, the angle of alternate bars being opposite.

7. In a hopper having a plurality of valleys in its bottom leading to discharge openings, the combination therewith of bars arranged to oscillate to and fro above the crests between the valleys, said bars being

arranged at oblique angles to the said crests, the angles at which half of the bars are arranged being opposite to those at which the other half are arranged, and means for oscillating said bars.

In testimony whereof, I have hereunto subscribed my name this 7th day of May, 1923.

OTTO ARAM.
